UNITED STATES PATENT OFFICE.

ROBERT L. ANDERSON, OF SAGUACHE, COLORADO.

FUR STRETCHER.

Application filed December 15, 1923. Serial No. 680,970.

The present invention relates to fur stretchers and is particularly adapted for stretching and supporting the pelts of fur bearing animals.

5 The principal object of the invention is to produce a device, of high efficiency for this purpose, and adapted for stretching pelts of various sizes within a reasonable range and with substantially equal efficiency.

10 Another important object of the invention is to generally improve upon devices of this nature by providing a fur stretcher having a simple construction, one which is reliable, inexpensive to manufacture, durable, and 15 well adapted for the purpose designed.

With the above and numerous other objects in view as will appear as the description progresses the invention resides in certain novel features of construction, and in 20 the combination and arrangement of parts as will be hereinafter more fully described and claimed.

In the drawing:

Figure 1 is an elevation of the structure; 25 Figure 2 is a detail perspective of one of the pelt leg-engaging clips; and

Figure 3 is an end elevation of one of the arms of the stretcher.

Referring to the drawing in detail it will be seen that the invention comprises a resilient frame 1 preferably formed of a single piece of spring metal bent into U-shape and, by reason of its inherent resiliency, having a tendency to contract. A bar 2 is pivotally mounted on one end of the frame 1 by means of a strap 3 and is provided with a series of notches 4 for engaging a pin 5 on the other terminal of the frame whereby the distance between the side members of the frame may be varied so that an outward tension may be placed upon the pelt which is disposed over the frame. The frame 1 comprises two arms 6 which are connected by the portion 7. A clip is mounted on 45 each arm 6 and consists of a single strand of resilient wire bent to provide a straight arm 8 having a large coil 9 at one end and a small coil 10 at the other end. The coil

9 is adapted to be disposed about the arm 6 on which the clip is disposed. A straight extension 11 extends from the small coil 10 and terminates in a hook 12 the rounded portion of which is abutted with an intermediate portion of the arm 8 so that the extension 11 is disposed in spaced parallel relation to the arm 8. These clips are used for engaging the leg portions of the pelt when the same is disposed on the frame.

It is evident that the clips may be moved longitudinally of the arms 6 and rotated thereon whereby the device may be utilized for various sizes of pelts and the clips may be readily engaged with the leg portions thereof owing to the fact that they rotate and slide on the arms.

The operation of the device will be understood by those skilled in the art from the drawings in connection with the description herein.

It is readily apparent that many changes may be made in the form, and details of construction and in the shape and size of the parts without departing from the spirit of the invention as hereinafter claimed.

What is claimed is:

A fur stretcher comprising a frame having a normal tendency to contract when expanded, and including a pair of resiliently connected side members, a pair of clips, one mounted on each side member, each of said clips including a straight transversely extending arm, a coil formed at one end of the arm and embracing the respective side member of the frame in such manner as to be rotatably and slidably adjustable upon the said member, a coil formed at the other end of the said arm and terminating in an extension extending parallel to and adjacent the arm, the said extension having a hook at its end having its bill presented outwardly, the back of the hook being held in engagement with the said arm through the resiliency of the last mentioned coil.

In testimony whereof I affix my signature.

ROBERT L. ANDERSON.
